UNITED STATES PATENT OFFICE.

AUGUST BUERMANN, OF NEWARK, NEW JERSEY.

DESIGN FOR A BRIDLE-BIT.

SPECIFICATION forming part of Design No. 13,458, dated November 28, 1882.

Application filed October 17, 1882. Term of patent 7 years.

To all whom it may concern:

Be it known that I, AUGUST BUERMANN, of Newark, in the county of Essex and State of New Jersey, have invented a new and useful Improvement in Designs for Bridle-Bits, of which the following is a specification.

My invention relates to the cheek-pieces of bridle-bits and to the pattern in which they are made; and it consists in the features substantially as hereinafter set forth.

Figure 1 is a side or face elevation of a cheek-piece. Fig. 2 is an edge view of the same.

The features of my design are principally those set forth in the upper part of the cheek. The top has the loop A, standing nearly at right angles with a vertical line on the cheek, the end B a little depressed. C is a loop portion, dropping down nearly at right angles with loop A. Below these loops is the neck S, and below this, on the right-hand side, the cheek widens out into a broad breast, D, in which the mouth-piece E is secured. Any variety of mouth-piece may be used, but the round head of it, F, shows on the face of the cheek as a part of my design.

The left-hand edge of the cheek, below the loop A, has a long curve, G, and then two short curves, H I. Below these and below the breast

are the curves J K, and below the curve K is the head of an eagle, L, and below this is a neck, M, connected with the shank N of the cheek; but the portions below the breast D and the curve I may be in varying forms; or it may be a straight section connecting the shank.

On the face of the cheek are wrought various ornamental figures, O, which admit of some slight variation from those shown, as also does the outline.

The top of the cheek is flared out, as seen at P in Fig. 2.

I claim—

1. The design of the upper portion of the cheek-piece, substantially as described and shown, embracing the loops A and C, neck S, breast D, curves G H I, and the head F, and the flared end P.

2. In combination with the upper cheek portion, as above set forth and claimed, the lower portion, embracing the curves J K, eagle-head L, neck M and shank N, and the ornamental lines O on the face of the whole.

AUGUST BUERMANN.
